ATTORNEY

INVENTOR
Morris Weinstein.

UNITED STATES PATENT OFFICE

MORRIS WEINSTEIN, OF NEW YORK, N. Y.

SUSPENDERS

Application filed September 12, 1930. Serial No. 481,433.

My invention has in contemplation the separate marketing of the four essential parts of a pair of suspenders, namely, the main or shoulder band, the back end, and the two front ends, so that these parts may be separately purchased for replacement purposes at a fraction of the cost of the ordinary unitary suspenders, or of the complete combination of my unitary parts and the suspenders forming the present invention embody in their structure features of construction which adapt them to that manner of merchandising the goods and for the facile detachment and replacement of a worn or broken part.

15 A further object of this invention is to make the suspender ends in such a manner that they may be used with and may be readily secured to a piece of elastic webbing, which is merely cut off from a length or 20 roll or webbing to comprise the main or shoulder straps, without making it necessary to hem, stitch, bind or overcast the raw or unfinished ends of the webbing, or to do anything therewith except to cut it to the desired length, the said ends being concealed 25 by the buckle or by the pad by which the upper ends of the front buttoning tabs are permanently flexibly attached to the buckle.

A further object of this invention is to 30 provide the front suspender ends with buckles permanently and irremovably attached thereto and of such a character that they securely and adjustably clamp within them the main shoulder band, and within which the unfinished ends of the shoulder bands may be concealed and covered, and through which the main bands may freely slide longitudinally when the buckles are unclamped.

35 Other objects of my invention will appear in the specification and claims below.

Referring now to the drawings forming a part of this specification and in which the same reference characters are used throughout the various views to designate the same parts;

Fig. 1 is a front elevational view of a pair of suspenders embodying my invention;

50 Fig. 2 is a front elevational view showing front of the buckle, of an end of the main

band or shoulder strap; and of the soft, flexible pad or cushion, permanently and irremovably connecting the upper ends of the buttoning tabs with the buckle;

Fig. 3 is a view similar to Fig. 2, but of 55 the opposite side of the parts therein shown;

Fig. 4 is a fragmentary, vertical, sectional view on the line 4—4 of Fig. 3;

Fig. 5 is a side elevational view of the parts shown in Figs. 1 to 4 inclusive;

Fig. 6 is a fragmentary, vertical, sectional view on the line 6—6 of Fig. 1; and,

Fig. 7 is a view similar to Fig. 4, but showing a slightly different mode of attaching a front suspender end to the main band or 65 shoulder strap.

The suspenders embodying my invention comprises four complete unitary parts which may be easily assembled to form a complete pair of suspenders, such as is illustrated in 70 Fig. 1.

The four parts or members are respectively, the main member 1, the back member 2 and two front members 3—3.

The main member 1 comprises a single 75 strip or band 4 of elastic webbing of the usual width which may be merely cut from a roll or spool of elastic webbing to the desired length.

The ends 4' of this strip may be raw or 80 unfinished, it being unnecessary to hem, stitch, bind or overcast said ends as will appear below, although of course, the said ends may be finished in any desired manner. But, the main aim and purpose of the present invention is to enable one to merely purchase a piece of webbing, of suitable width, and of a length suitable for the purchaser's personal needs, the same being cut by the shopkeeper to the desired length from a spool or 85 roll of elastic webbing, and having purchased that length to require the purchaser to do nothing further therewith except to pass it through the back member 2 and to secure the front ends thereof to the front members 3, as will be explained more fully below.

The back number 2 preferably comprises a pair of buttoning tabs 5—5, the upper ends of which are covered by small pieces 6—6 of 100

leather or other suitable flexible material lying flat on the opposite sides of the buttoning tabs 5—5 and secured thereto by stitching 7.

5 The upper ends of these pieces 6 also cover the two ends of a relatively short length of elastic webbing 8, said ends being brought together, preferably after the length has been passed through a metal loop or slide 9 to lie 10 flat against each other. The said pieces 6—6 are preferably also stitched to the lower ends 15 of said elastic webbing 8 by the stitching 7 and when the stitching is all finished, these pieces 6 substantially stuff with the lower ends of the webbing 8 and with the upper ends of the tabs 5, form a thin, flat, soft, flexible pad 10 which is comfortable to wear and does not show through the clothing. The tabs 5, the pad 10, the folded webbing 8, and 20 the loop or slide 9, carried thereby, form a complete unit which I have herein termed the back member. The folded or looped piece of webbing 8, thus forms the yielding elastic back strap of the back member 2.

25 The front members 3 are alike and each comprises a pair of front buttoning tabs 11, the upper ends of which lie between and are enclosed by a relatively small piece 12 of flexible material such as leather or strong 30 firm webbing and it is preferably folded to lie on opposite sides of the upper ends of the front buttoning tabs 11 and is secured thereto by the stitching 13. Before stitching, however, the small piece 12 is passed through 35 a slot 14 at the lower edge of the buckle 15.

When so connected together by stitching, the piece 12 with the upper ends of the front buttoning tabs 11 enclosed thereby, becomes a flexible, soft, thin pad 16, similar to the pad 40 10 on the back member 2 but permanently attached with the buckle 15 instead of with the back strap 8. The front member 3, thus formed, constitutes a unit construction comprising the front buttoning tabs 11 and the 45 buckle 15 permanently and flexibly secured to the top or upper ends of the tabs 11 by the soft, flexible pad 16.

The front plate 15' of the buckle is preferably flat and is preferably of a size sufficient 50 to substantially cover and conceal behind it the back plate 15" of the buckle to clamp between them the main strap of elastic webbing 4 when inserted between the plates.

The unfinished ends of the unfinished ends 55 4' of the webbing 4 forming the main member 1, may be concealed within the buckle 15 by the front plate 15' or it may be inserted between the plates and then inserted rearwardly through slot 14 in the back plate 15" of the buckle and behind the upper end of the pad 16 and in either event, the unfinished end 4' is covered and concealed by the front member 3.

It will now be seen that I have provided a 60 suspender made up of four complete units,

any one of which may be readily separated from the others and a new piece substituted therefor. Thus, if the elastic webbing forming the main member 1 loses its resiliency, all that one has to do is to free the ends thereof from its engagement with the front members 3, draw the webbing 4 freely out from the loop or slide 9; insert a new piece of webbing 4 through the slide 9 and attach the ends thereof to the front members by the buckles 15 of the front member 3. Similarly if one of the front members 3 were to become broken or worn, one only has to unbuckle it and replace the member with a new or substituted front piece 3. In both instances, last above referred to, the new part or piece can be purchased at a small fraction of the cost of a new pair of suspenders complete and the fullest service is obtainable from the article.

Since it is desirable to have both shoulder straps of the suspenders look alike when the suspenders are worn and since the attachment of the webbing 4 to the back member is made by merely looping the webbing through the slide or runner 9 with the result that one side of the webbing is exposed over one shoulder and the other side of the webbing is exposed over the other shoulder, it is desirable that the webbing be either plain or that it be woven in such a manner that the opposite sides of the webbing are exactly alike, thus displaying the same pattern or ornamentation on both shoulders.

In the drawings I have illustrated, the main member 1 as having a pattern 17 woven into the webbing and showing exactly alike on opposite sides thereof so that both shoulder straps present the same appearance when the article is used.

Having thus described my invention, what I claim and desire to protect by Letters Patent of the United States is:

1. In a suspender, the combination of four suspender members each constituting a separable and replaceable unit, namely: a main member, a back member and two like front members; said back member comprising a pair of buttoning tabs, a slide and a back strap permanently connecting said slide with the upper ends of said buttoning tabs, each front member comprising a pair of buttoning tabs and a buckle permanently, flexibly secured to the upper ends of said tabs; and said main member forming shoulder straps and comprising a single length of elastic webbing, alike on both sides, adapted to be severed from a longer piece of elastic webbing, and the ends of which may be raw and unfinished, said main member being merely passed through said slide on said back strap and being freely slide longitudinally therethrough, the ends of said main member being clamped within said buckles and so adjustably and removably secured to said front 130

members by said buckles, the ends of said main member being covered and concealed by said front members.

2. In a suspender, the combination of four members each constituting a separable and replaceable unit structure, namely: a main member, a back member and two like front members; said back member comprising a pair of buttoning tabs, a slide, an elastic back strap passing through and freely sliding longitudinally through said slide, the ends of said back strap and the upper ends of said tabs being brought together in substantial alinement, covering pieces of strong, flexible material covering the upper ends of said tabs and the lower ends of said back strap and stitched thereto, whereby said back strap and said tabs are connected together by a pad stuffed with the ends of said buttoning tabs; each front member comprising a pair of buttoning tabs, a buckle and a strip of flexible material stitched to the upper ends of said buttoning tabs, whereby said tabs are permanently, pivotally connected to said buckle by a soft pad stuffed with the upper ends of said tabs; said main member comprising a single length of elastic webbing looped through and freely sliding longitudinally through said slide on said back strap and having its ends securely, adjustably clamped to and concealed by said front members.

In witness whereof, I have hereunto set my hand this third day of September, 1930.

MORRIS WEINSTEIN.
